CLAIM

The ornamental design for a gasket segment, as shown and described herein.

DESCRIPTION

FIG. 1 is a perspective view of a front side of the gasket segment in accordance with the new design.

FIG. 2 is a perspective view of a rear side of the gasket segment of FIG. 1.

FIG. 3 is a perspective view of a bottoms side of the gasket segment of FIG. 1.

FIG. 4 is another perspective view of the bottom side of the gasket segment of FIG. 1.

FIG. 5 is a top plan view of the gasket segment of FIG. 1.

FIG. 6 is a bottom view of the gasket segment of FIG. 1.

FIG. 7 is an elevational view of the front side of the gasket segment of FIG. 1.

FIG. 8 is an elevational view of the rear side of the gasket segment of FIG. 1; and,

FIG. 9 is an elevational view a lateral side of the gasket segment of FIG. 1, which is a mirror image of the opposing lateral side thereof.

(Continued)

The broken lines of the disclosure represent unclaimed portions of the gasket segment and form no part of the claimed design.

1 Claim, 3 Drawing Sheets
